UNITED STATES PATENT OFFICE

WILLIAM S. BOYD, 3d, OF PHILADELPHIA, PENNSYLVANIA.

IMPROVEMENT IN TINNERS' FIRE-POTS.

Specification forming part of Letters Patent No. 222,859, dated December 23, 1879; application filed November 10, 1879.

To all whom it may concern:

Be it known that I, WILLIAM S. BOYD, 3d, of Philadelphia, in the county of Philadelphia and State of Pennsylvania, have invented certain new and useful Improvements in Tinners' Fire-Pots; and I do hereby declare that the following is a full, clear, and exact description of my invention, which will enable others skilled in the art to which it appertains to make and use the same, reference being had to the accompanying drawings, and to the letters of reference marked thereon, which form a part of this specification.

This invention relates to an improvement in tinners' fire-pots; and it consists in the construction, combination, and arrangement of parts, as will be hereinafter more fully set forth, and pointed out by the claims.

In the annexed drawings, which fully illustrate my invention, Figure 1 is a side elevation. Fig. 2 is a section on line *x x* of Fig. 1; and Fig. 3 is a section on line *y y*, Fig. 2.

Like letters of reference indicate like parts.

A represents the outer case, of any desired material, having the reservoir *F* hinged to its base, and the top *G* to its upper portion. The top *G* may be of any desired form, and it is provided with openings *j* for the egress of smoke, &c., and it is also provided with the ears *i*, to which is attached a bail, *H*. *d d* represent the hinges by which the top is attached to the part *A*.

To the front of the part *A* is secured an apron, *I*, as shown, under which are the openings *l*, provided with sliding doors *h*. These sliding doors have their bases bent upward V-shaped, whereby the iron can easily be inserted by pressing against the base of the door. At the base of the openings *l*, and inclining therefrom downward toward the flame, are aprons *o*, on which the iron rests.

C is a shield at the back of the case *A*, against which the point of the iron rests, and which prevents the same from going beyond the flame. *E* represents an air-chamber formed in the base of the case *A*, in which is located the wick-chamber *E'*.

The wick-tubes *a'*, having the wicks *a*, pro-

ject up through openings in the upper plate of the air-chamber.

p represents a shaft passing through the wick-chamber *E'*, and having thereon a spur-wheel, *b*, which gears with another spur-wheel, *c*, on a shaft, *q*. Both these wheels impinge against a wick, and by turning the shaft *p* the two wicks may be raised or lowered at the same time, as shown.

K is an opening in the outer case, communicating with a pipe, *B*, through which air is drawn into the air-chamber *E*. *F* represents the reservoir which forms the base of the device, which is provided with an opening in its top to allow the wicks to enter, and is also provided with flanges *f'*, on which the wick-chamber *E'* rests. *ee'* represent spring-latches, which hold the top, case, and reservoir together when in use. It is obvious that the apron *I* may be placed inside the case and perform its functions equally well.

J represents a sliding door of mica or other transparent material, to enable the operator to light the device at will.

The upper or top plate of the air-chamber is movable, and can be taken out and replaced at will.

By this arrangement a fire-pot is produced that can be used in the open air without any inconvenience, and any number of coppers or irons can be heated by increasing the length of the device and the number of wicks, &c.

It is cheaply and easily constructed, and not liable to get out of repair.

The top *G*, as shown, acts as a ventilator.

By the use of this device, also, there is an immense saving in the cost of fuel. There is no waste, as the flame can be lighted and extinguished at will.

Having thus fully described my invention, what I claim as new, and desire to secure by Letters Patent, is—

1. The case *A*, shield *C*, apron *I*, and openings *l*, with sliding doors *h*, having V-shaped bottoms, and the apron *o*, substantially as and for the purpose set forth.
2. The top *G*, having openings *j*, base or reservoir *F*, air-chamber *E*, wick-chamber *E'*,

and case A, in combination with the hinges *d d'* and spring-latches *e e*, substantially as and for the purpose set forth.

3. The case A, opening K, tubes B, air-chamber E, wick-chamber E', wick-tubes *a'*, wicks *a*, in combination with the reservoir F and top G, hinged to the case, the openings *l*, with sliding doors *h*, rest I, door J, and shield C, substantially as and for the purpose set forth.

In testimony that I claim the foregoing as my own I have hereto affixed my signature in presence of two witnesses.

WM. S. BOYD, 3D.
